UNITED STATES PATENT OFFICE.

GEORGE SCHERER, OF JACKSON, MICHIGAN, ASSIGNOR TO HAYES WHEEL COMPANY, OF JACKSON, MICHIGAN.

SPOKE-MITERING MACHINE.

1,263,127.

Specification of Letters Patent. Patented Apr. 16, 1918.

Application filed August 30, 1916. Serial No. 117,714.

To all whom it may concern:

Be it known that I, GEORGE SCHERER, a citizen of the United States, residing at Jackson, Michigan, have invented certain new and useful Improvements in Spoke-Mitering Machines, of which the following is a specification.

This invention relates to improvements in spoke mitering machines.

10 The main objects of this invention are:

First, to provide an improved construction of work table for such mitering machine.

15 Second, to provide an improved construction of cross head and cutting means.

Third, to provide an improved means of retaining the spoke effectively in position to secure accurate formation of the mitered hub end of the spoke.

20 Further objects, and objects relating to details and economies of construction and operation will definitely appear from the detailed description to follow.

I accomplish the objects of my invention 25 by the mechanism described in the following specification. The invention is clearly defined and pointed out in the claims. A preferred embodiment of my invention is illustrated in the accompanying drawing, forming a part of this specification, in which:

Figure I is a side elevation of my improved spoke mitering machine, a portion of the same being cut away to show the adjusting means for the table.

35 Fig. II is a detail vertical section showing the train of the gearing from the driving pulley to the crank shaft, taken on the broken line 2-2 of Fig. I.

Fig. III is a front elevation of the machine, the lower part of which is broken away.

Fig. IV is a detail horizontal section showing the cross head and the standard taken on line 4-4 of Figs. I and III.

45 Fig. V is an inverted plan view of the cross head with the cutters and the cutter blocks arranged thereon.

Fig. VI is a top plan view of the table, showing the spoke positioning means on the same, with the position of the spoke shown by dotted lines.

50 Fig. VII is an enlarged partial detail vertical section through the cross head, showing the longitudinal adjusting means of the

cutter carrying blocks, taken on line 7-7 55 of Fig. I.

Fig. VIII is a detail vertical section through the tight and loose driving pulleys, showing the manner in which the shear pin is used in this machine, taken on line 8-8 60 of Fig. I.

In the drawing, similar numerals of reference refer to similar parts throughout the several views, and the sectional views are taken looking in the direction of the little 65 arrows at the ends of the section lines.

The machine shown herein is adapted to bevel or miter the hub ends of the spokes after the same have been turned and prior to assembling the same into a wheel. The 70 hub end prior to mitering is either square or rectangular in cross section.

My machine consists of the upright standard 1 having an integral base 2. The work table 3 is pivotally mounted to the standard 1 on the pin 4, so that it may be readily tilted.

On the driving pulley shaft 5 is mounted tight and loose pulleys 6 and 7. The usual belt shifter, comprising a handled rod 40 80 provided with the fingers 30 suitably supported on the standard 1, is provided. The driving shaft 5 is rigidly secured to the standard 1, and the driving pulley 7 is connected by means of pin 38 through flanges 85 37 to the driving pinion 8. The pinion 8 meshes with the intermediate driving gear 9. Gear 9 is connected to an intermediate driving pinion 10, the two gears turning on an intermediate shaft 11, said shaft being fixed 90 in the standard 1. Pinion 10 meshes with the crank shaft gear 11' keyed to the rear end of crank shaft 12, which is journaled in the standard 1. At the front end of crank shaft 12 is securedly keyed the disk crank 13. 95

The disk crank 13 connects by a wrist pin 14, pitman 15 and pin 16 to the vertically reciprocating cross head 17. This cross head has a tongue on its rear face adapted to slide in the dove-tail guides of the standard 1, see 100 Fig. IV. The cross head pin is securely retained in a pair of cross head lugs 18, as shown. This cross head carries the reciprocating beveled cutter knives which cut the miters on the spokes. The knives are carried on adjustable knife carrying blocks 19, which are provided with dove-tailed ribs 19' which are engaged in suitable dove-tailed

seats 17' on the under side of the cross head 17. When the knife carrying blocks are adjusted, they are securely locked in position by set screws 17".

5 The knife holders 20 are provided with vertical bracket seats 21, on which are formed seats to receive the vertically reciprocating beveled knives 22. These knife holders are made identical and symmetrical, and each is pivoted to its carrying block 19 at 26, and its angle is adjustable by the set screw 27 disposed in the curved slot 28 in each said knife holder 20, see Fig. V. The knives are beveled on their back sides, 15 or the sides toward the standard and have beveled cutting edges, as seen in Fig. I and III.

The knife carrying blocks 19 are adjustable, as indicated, the means for adjusting comprising the bracket 24, see Figs. 20 I and VII, secured to the cross head 17, the same overhanging the end of the block 19. Each is provided with an adjusting screw 23 engaging in a screw-threaded bore in said 25 block. Collars 25, 25 are on each screw 23, embracing the bracket 24, see Fig. VII, to hold the screw in fixed longitudinal relation and make it effective.

From this explanation, it will be observed 30 that the knives are adjustable to and from each other, and the angle of the same can be sufficiently varied to secure the proper mitering of any design of spoke now in practical use. The knives, being tapered 35 and beveled toward the hub end of the spoke, cut the wood in a line of least resistance and effectively trim the same to a perfect miter.

On the table 3 and within the angle 40 formed by the knives is the cutter block 29. On top of the table also is placed the small working table 30 which rests on suitable blocks 31. At the end of table 30 and near the cutting block 29 is fastened a pair of 45 guide stop pieces 32. See Figs. I and VI. At the other end of the table is placed a V-block 33. When a spoke is put in the machine the hub end of the same is laid on the cutting block 29 and the head of the spoke 50 is drawn against the guides 32 while the end of the barrel rests in the V-groove in the block 33, this position being shown with the spoke dotted in Fig. VI. When the machine is in operation and the knife is reciprocating the same will slice off the portion 55 of the hub end of the spoke required to give the necessary angle to the same for the assembling in the wheel.

The table 3 is tilted about the pin 4 by 60 a suitable elevating screw 34, supporting the table as shown in Fig. I. The hand wheel 35 on the screw serves to manipulate the same. The lock wheel nut 36 locks the same in place. The knives here used are 65 similar to those used in a wood worker's

trimmer. The blades have a rearward bevel as shown.

By forming the knives oblique at the back side and beveling their cutting edges and reciprocating them in substantially vertical relation to the cutting block 29, it is found that the knives have a drawing effect and force the head of the spoke against the guide stops 32, thus retaining the spoke effectively in position, while at the same time the knife 75 cuts away the surplus wood along the line of least resistance, making a perfect flat jointed surface. By varying the elevation of the outer or rim end of the spoke by tilting the table, the required dish can be given 80 to the wheel.

Because of the perfection of the action of the machine, all spokes are cut substantially alike and the necessity for any rasping or trimming of the wheel between the spokes 85 to give a smooth finish in the completed wheel is entirely obviated, it only being necessary in some instances, to use a little sand paper to smooth the surface.

I have illustrated and described my improvements in detail in the form in which I have embodied the same for use. I have not attempted to illustrate or describe possible modifications and variations in structural details, as I believe the disclosure 95 made will enable those skilled in the art to embody my improvements as conditions may require. I desire, however, to be understood as claiming my improvements specifically in the form illustrated as well as broadly 100 as appear in the appended claims.

Having thus described my invention, what I claim as new and desire to secure by Letters Patent:

1. In a spoke mitering machine, the combination with a suitable standard, of a vertically reciprocating cross-head, a pair of cutter knives carried thereby oblique on their rear sides and with beveled edges, a work-table with a cutter block corresponding to the head of the hub end of the said finished spoke, and stop means disposed at each side of the spoke to engage the enlargement toward the hub end at a point in close proximity to the plane of each of said cutting knives, coacting for the purpose specified. 105

2. In a spoke mitering machine, the combination with a suitable standard, a vertically reciprocating cross head, a pair of cutter knives carried thereby oblique on their rear sides and with beveled edges, a work table with a cutter block corresponding to the head of the hub end of the said finished spoke, and stop means disposed at each side of the spoke to engage the enlargement toward the hub end, coacting for the purpose specified. 110

3. In a spoke mitering machine, the combination with a suitable standard, a ver- 115

5 tically reciprocating cross head, a pair of cutter knives carried thereby, a work table with a cutter block corresponding to the head of the hub end of the said finished spoke, and stop means disposed at each side of the spoke to engage the enlargement toward the hub end at a point in close proximity to the plane of each of said cutting knives, coacting for the purpose specified.

4. In a spoke mitering machine, the combination with a suitable standard, of a vertically reciprocating cross-head, a pair of adjustable cutter knives carried thereby oblique on their rear sides and with beveled edges, a work-table with a cutter block cor-

10 responding to the head of the hub end of the said finished spoke, and stop means disposed at each side of the spoke to engage the enlargement toward the hub end at a point in close proximity to the plane of each of said cutting knives, coacting for the purpose specified.

15 In witness whereof I have hereunto set my hand and seal in the presence of two witnesses.

GEORGE SCHERER. [L.S.]
